EXPANDED METAL SHEET

Bruce Hehn, St. Clairsville, Ohio, assignor to Wheeling Steel Corporation, Wheeling, W. Va., a corporation of Delaware

Filed Jan. 20, 1966, Ser. No. 705

Term of patent 14 years

(Cl. D54—2)

FIG. 1

I claim:

The ornamental design for an expanded metal sheet, as shown and described.
